MACHINE FOR GLUING TEXTILE FABRICS.

No. 922,962.

Specification of Letters Patent.

Patented May 25, 1909.

Application filed June 5, 1908. Serial No. 436,822.

To all whom it may concern:

Be it known that we, FREDERIK CHRISTIAN SCHRÖDER, Set. Marcus Sidealle 4, Copenhagen, and JÖRGEN SELDAL, Jægersborg Alle, Gentofte, by Copenhagen, Denmark, citizens of the Kingdom of Denmark, and residents of Copenhagen, Denmark, directors, have invented certain new and useful Improvements in Machinery for Gluing Textile Fabrics, of which the following is a specification.

Owing to the rapid growth of the textile industry of late years textile fabrics are at present used for more various purposes than formerly. The fabrics most often used are made of cloth arranged in several layers glued together. It appears, however, that there is considerable difficulty in gluing the cloth layers and still greater difficulty in rendering the gluing durable.

Our invention comprehends a machine for the automatic continuous gluing of textile fabrics, and is so arranged that in its action it divides into separate groups the various layers of cloth to be glued and brings the layers together in such manner that each group is glued independently of the others, the pressure necessary for the gluing being utilized in the most effective manner.

Reference is to be had to the accompanying drawing forming a part of this specification, in which the figure is a diagram showing the central cylinder, the pressure rollers, the layers of cloth divided into groups and forced together by the pressure rollers, the view further showing the glue basin and the rolls of cloth for supplying the stock.

The tables are shown at 1 and revolvably supported over them are the cloth rolls 2.

The separate layers of cloth are shown at 2^a, these layers being divided into groups, as shown, and passing over guide rollers 3.

A glue basin is shown at 4 and in it are arranged guide rollers 5.

Scrapers are shown at 6 and engage the layers of cloth as they emerge from the glue basin.

Pressure rollers are shown at 7, 9, 10, 11, and are spaced apart and disposed in immediate proximity to a large cylinder 8. These pressure rollers squeeze the different groups of layers of the cloth and cause thorough adhesion therebetween. The pressure rollers are so arranged that they do not act at the

same instant upon the cloth and are, as nearly as practicable, independent of each other. Another pressure roller 12 acts upon the fabric when it is nearly finished. The pressure rollers 7, 9, 10, 11 are severally mounted upon levers 13, 14, 15, 16, and 60 pivotally connected with these levers are rods 17, 18, 19, 20. These rods are threaded at their free ends and mounted upon these threaded ends are nuts 21, 22, 23, 24 for adjusting the levers 13, 14, 15, 16.

Stationary supports 25, 26, 27, 28 serve as stops for the nuts. The pressure roller 12 is journaled upon a lever 29 which is mounted upon a stationary bracket 30. A threaded rod 31 is journaled upon the lever 29. A nut 70 32 is revolvably mounted upon this threaded rod. A stationary bracket 33 serves as a stop for the nut 32.

The operation of our device is as follows: The parts being in position, as indicated in the figure, and power being applied to the cylinder 8 so as to turn the same, the various layers of cloth are drawn through the glue, scraped by passing the scrapers 6, separated into groups, squeezed together by pressure of 80 the rollers 7, 9, 10, 11, and finally, when nearly finished, pressed again by the pressure roller 12. The operator, by adjusting the various nuts 21, 22, 23, 24, can regulate the pressure exerted by the pressure rollers 7, 9, 85 10, 11. The operator also, by turning the nut 32, can regulate the pressure exerted by the roller 12. It will be noted that the undermost layers of the cloth pass under the pressure roller 7 which squeezes these layers into 90 a compact single layer and forces this layer directly against the large cylinder 8. The next group of layers is applied somewhat farther away by aid of the roller 9, being pressed downwardly upon the layers applied 95 by aid of the roller 7 and which are now practically a single layer but adhesive. The action of the other pressure rollers will readily be understood from the above description. The fabric being finished consists, of course, 100 of cloth laminæ and may be washed out, imbued with waterproof materials or passed through any other process desired in view of the contemplated future use of the finished fabric. The finished material is laid away 105 as fast as formed and may be afterward worked up into mats, shoe soles or analogous articles.

Having thus described our invention, we claim as new and desire to secure by Letters Patent:

In a machine of the class described, means for supporting a plurality of rolls of cloth and for guiding them through the machine, means for supplying glue to both sides of each layer of cloth, means for dividing said layers into a plurality of groups, means for 10 pressing the members of a group together,

and means for finally pressing the groups together.

Signed by us at Copenhagen, Denmark this 19th day of May 1908.

FREDERIK CHRISTIAN SCHRÖDER,
JÖRGEN SELDAL.
